COMBINATION CONTAINER OPENER AND BOTTLE SEAL BREAKER

Frank Amil Turgeon, Jr., Rockville, Md.

Application June 8, 1948, Serial No. 146,819

Term of patent 3½ years

(Cl. D22—2)

To all whom it may concern:

Be it known that I, Frank Amil Turgeon, Jr., a citizen of the United States of America, residing at Rockville, in the county of Montgomery and State of Maryland, have invented a new, original, and ornamental Design for a Combination Container Opener and Bottle Seal Breaker, of which the following is a specification, reference being had to the accompanying drawing, forming a part thereof.

In the drawing:

Figure 1 is a side elevation of the combination container opener and bottle seal breaker showing my new design.

Figure 2 is a front elevation.

Figure 3 is a bottom plan view.

Figure 4 is a vertical section taken on the line 4—4 of Figure 2.

Figure 5 is a top plan view.

I claim:

The ornamental design for a combination container opener and bottle seal breaker, as shown.

FRANK AMIL TURGEON, JR.
